UNITED STATES PATENT OFFICE

JOHN SCHNEIDER, OF ROSELLE PARK, NEW JERSEY, ASSIGNOR TO THE DELTA STAR ELECTRIC COMPANY, OF CHICAGO, ILLINOIS, A CORPORATION OF ILLINOIS

SWITCH

Application filed August 22, 1927. Serial No. 214,501.

My invention relates in general to electric switches, and more particularly to such switches as are known in the art by the term load break disconnect switches.

5 In the electrical art the usual practice is to place disconnect switches in series with circuit interrupters and like apparatus so that these devices may be isolated from the rest of the system of electrical distribution and 10 worked upon with safety. It is obvious that in such use the disconnect switches do not have to be designed to break the load circuit since this is broken by the circuit interruptor. 15 The function of a disconnect switch is merely to isolate a particular piece of apparatus with which it is associated. The only current that it has to break is the charging current which is relatively small in comparison with the load. It often occurs, however, that it is 20 necessary to operate these disconnect switches under load. Under these conditions, a great deal of trouble is encountered because the disconnect switches are ordinarily not designed 25 to break the load circuit. Very often a disastrous arc is formed and great difficulty occurs in opening the circuit and in addition the disconnect switch may be destroyed. In view of the foregoing, it is therefore, highly 30 desirable to provide a disconnect switch 35 which may be used to open the load circuit if it becomes necessary.

One of the objects of my invention is to provide a disconnect switch which may be used to open the circuit through which the 35 load is passing.

Another object is to provide a disconnect switch in which there are two current conducting paths, one of them that is used normally to pass the main current and the other 40 of which is used to temporarily carry the main current when the first circuit is broken.

Another object is to provide means in my improved disconnect switch for opening this second current path with a very fast snapping motion and in a manner in which, if an arc is formed, it is very quickly cut off.

Still another object is to provide a disconnect switch which may be closed under load and in which the main circuit is preliminarily closed through the arcing horns,

after which the main circuit is closed through the usual switch contacts.

There are other objects of my invention which, together with the foregoing, will be described in the detailed specification which is to follow, taken in conjunction with the accompanying drawings.

In its preferred form, my invention consists essentially of two insulator stacks mounted upon a base, one of these insulator stacks carrying the stationary contact member or terminal together with the stationary arcing horn, the other member carrying the movable arcing horn affixed to the top thereof. A suitable contact making member adapted to engage the stationary contact member, is mounted upon an insulator stack attached to said base midway between the two stationary insulator stacks. The middle insulator stack is pivoted so that it may be rotated. A suitable lever mechanism is arranged and attached to the movable insulator stack so that it may be rotated. When the switch is closed the arcing horns contact first and thereafter the main circuit is established through the contact making member and the stationary contact member. When the switch is opened the main circuit is broken first through the main contacts and after the movable contact member has gained considerable speed it forces the arcing horns apart with a rapid snapping movement.

Referring now to the drawings:—

Fig. 1 is a side elevation of my improved disconnect switch in its closed position;

Fig. 2 is a side elevation of the disconnect switch in its open position;

Fig. 3 is a top plan view of the switch shown in Fig. 2.

Fig. 4 is a fragmentary view showing the 90 forked end of the arcing horn.

Referring now to the drawings in detail, in which like reference characters in the various figures designate similar parts, reference character 5 generally denotes a suitable supporting structure for my improved disconnect switch designated generally by the reference character 6. The supporting structure 5 carries a channel base 7, upon which is mounted two insulator stacks 8 and 9 of the

usual construction. The insulators are fixed permanently to either end of the channel base. 7. A metallic cap 10 is cemented to the top or crown of the insulator 8 and the top of this cap forms a straight surface or platform. A member 11 of copper or other suitable conducting material having extensions 12, 13 and 14 is permanently attached to the top of the metallic cap 10. The extension 12 of the member 11 forms the stationary contact member of the switch. The extension 13 forms the usual lug to which the electric circuit is usually connected. The upwardly extending extension 14 serves as a supporting member for the arcing horn 15 which is affixed in a socket in the member 11. The arcing horn 15 is forked a short distance from its upper extremity and is bent inwardly as shown.

20 The other insulator stack 11 has a metallic 16 cemented to the crown thereof, the top of which cap forms a platform to which the member 17 of copper or other suitable conducting material is permanently attached. 25 The member 17 carries an extension 18 which forms the usual terminal lug. The member 17 also carries an extension 19 on either side thereof, which is bent upwardly to form a pivot for the movable horn support 20. The 30 movable horn support 20 has two sides slightly spread apart except at their upper extremity where they are joined together to form a socket for the movable arcing horn 21, which is permanently affixed therein. The 35 movable arcing horn 21 is adapted to cooperate with a stationary arcing horn 15, that is, it is adapted to rest within the forked end of the stationary arcing horn. A bumper plate 22 is permanently attached to the horn support 20 with its back projecting over the support. A pin 23 which projects over the side of the movable support 20 is permanently held in place by the bumper plate 22. The 40 projecting sides of the bumper plate 22 are 45 cut away a short distance from the pin 23, (see Fig. 3).

50 A third insulator 25 is mounted midway between the stationary insulators 8 and 9. The stationary insulator 25 is affixed to a pin 26 that extends through a slot 27 in the base plate 7. The pin 26 is pivoted in the bracket 28 attached rigidly to the base plate 7. The pin 26 carries the counter balancing weight 29 adjustably attached to its lower extremity to counter balance the weight of the movable insulator 25. An adjustable stop 30 may be rigidly mounted upon the base plate 7 to limit the swinging movements of the pin 26. 55 A link member 31 is pivotally attached to the pin 26 at 32 and is operative to rotate the movable insulator 25 through the operation of the crank lever 33, link 34 and the operating lever 35. This system of connecting links and 60 levers for operating means to revolve insula-

tor 25 may be of any usual or well known construction.

Another cap 40 is mounted upon the crown of the insulator 25 and provides a supporting means upon which the member 41 may be mounted. The member 41 may be of copper or other suitable conducting material and carries an extension 42 which forms a terminal connecting lug of the usual type. The member 41 is also provided with an upwardly extending extension upon which is mounted the contact making member 44. This member may consist of two spring contact jaws adapted to fit over the contact member 12 with which it operates. A sleet hood 45 of box-like construction with the lower side open, is pivotally attached to the lower end of the contact making terminal 44 at 46. The sleet hood 45 is provided with two extending links 47 which are extensions of the sides of the sleet box itself. These extensions 47 are provided with hooks 48 at their extremities and together with the stopping pin 23 form means for limiting opening movement of the switch. A link member 49 is pivotally attached to the extensions 47 at 50 and to the movable horn support 20 at 51. The link member 49 is of box-like construction with the lower side being open so as to fit over the supporting members 20 when the switch is opened. One portion of the link member 49 is slightly cut away, as may be seen at 53 in Fig. 3, so that it may be pivoted to the supporting member 22. A flexible conductor 54 connects the terminal 18 on the stationary insulator 9 with the terminal 42 on the movable insulator 25 in order to provide a good conducting path to the movable contact making member 44. The flexible conductor 54 is passed over pins 55, 56 and 57 in the horn supporting member 20 and in the extensions 47 of the sleeve box 45 in order to hold the flexible conductor in such position as it will not interfere with the switch operation.

Having described the improved mechanical construction of my novel disconnect switch I will now explain its operation. For this purpose it will be assumed that the disconnect switch is in a closed position and it is desirous to open it under load. Under these conditions, the lever 35 will be manually moved downward thereby bringing about the movement of the pin 26 carrying the movable insulator 25 in a clockwise direction by means of the crank lever 33 and the links 31 and 34. It will be obvious that in the rotation of the insulator 25 the engagement of the contact making member 44 with the contact member 12 is broken. This operation does not break the electrical circuit through the switch because the arcing horns 15 and 21 are still in engagement. As the insulator 25 is rotated the extensions 47 are moved closer to the bumper plate 22 carried by the arcing horn support 20. When the extension 47 finally

contacts the bumper plate 22 the movable insulator 25 will have considerable momentum and the arcing horn 21 will be moved from engagement with the arcing horns 15 with a snapping, rapid movement. The further rotation of the insulator 25 brings the hooks 48 of the extension 47 in such a position as to engage the pin 23 on either side herewith forming a limit to the movement of the arcing horn. When this occurs the switch is in the position shown in Fig. 2 and the rotation of it ceases. At this point also the stopping member 30 carried by the base plate 7 may serve to stop the movement of the rotary insulator 26. The opening of the arcing horns 15 and 21 bring about breaking of the main electrical circuit through the switch. It will be seen by tracing the path of the movable arc horn 21, as shown by the dotted line of Fig. 1, that it is curved in such manner that the arc will be broken very readily. This occurs because the movable arcing horn 21 takes an upward movement to break the arc, this upward movement is much more efficacious in breaking the arc than if the movement were simple horizontally away from the stationary arcing horn 15. By reason of the lost motion connection including the link between the extension 47 and the movable support 20 the movable arcing horn is moved very rapidly to an open position with the snapping movement.

In the open position of the switch the box-like sleet shield completely encloses the contact making members 44 so as to protect it from moisture. This permits the switch to be left open under all conditions of weather for any length of time with the assurance that it may be closed without difficulty.

By using this construction of disconnect switch in which the main circuit through the switch is first interrupted and then the auxiliary circuit over which the current flows when the main circuit is opened is interrupted, the disconnected switch may be used to disconnect the load. This arrangement in which the circuit through the arcing horn of the switch is opened with the rapid snapping movement extinguishes the arc very quickly if one should develop. There is no possibility of an arc forming between the contact making member 44 and the contact member 12 at this time because of their distance apart.

When closing the switch by a movement of the lever 35 in the opposite direction, the same operations as described occur. That is, the hook 48 and the pin 23 are engaged and the links 47 move the support 20 rapidly throwing arcing horn 21 into contact with the horn 15. At this time and while the movable insulator is at its center point in its closing movement, the hook 48 disengages the pin 23. Thus a contact is first established between the arcing horn 21 and the horn 15, and then the contact making member 44 en-

gages the contact member 12. This provides a very convenient method of closing a circuit to supply the load. It is to be noted that when the movable insulator moves beyond its center position in its closing movement the weight of the insulator turns to close the circuit between the contact 44 and 12 with a rapid movement.

It is obvious, of course, that while I have described only a single disconnect switch, that these switches may be operated in gangs in the usual manner in order to interrupt a polyphase circuit. Under these conditions the operation of the various switches in the gang occurs in the same manner as has been described.

I desire it to be understood that, although I have disclosed and described a preferred form of my invention, the invention is not limited thereby, but only insofar as defined by the scope and spirit of the appended claims:

I claim:

1. A switch comprising a main contact member and an auxiliary contact member, a stationary insulating support for said members, a movable main contact making member and a movable auxiliary contact making member, a movable insulating support for said main contact making member, means, including a stationary insulating support for said auxiliary contact making member, and an actuating connection between the two movable contact making members for actuating the auxiliary contact making member upon actuation of the movable insulating support.

2. A switch comprising a main contact member and an auxiliary contact member, an insulating support for both of said members, a movable main contact making member and a separately movable auxiliary contact making member, insulating supporting means for said contact making members, and, a collapsible link connection pivotally connecting the two members and including one link pivoted to one of the contact making members and another link pivoted to the other contact making member with a pivotal connection between the two links.

3. A switch comprising a main contact member, an auxiliary contact member, an insulating support for both said members, a main contact making member, an auxiliary contact making member, insulating supporting means for said contact making members, the insulating supporting means including a rocking insulator for the main contact making member, and a lost motion pivoted link connection between said contact making members.

4. A switch comprising a main contact member, an auxiliary contact member, an insulating support for said members, a main contact making member, an auxiliary contact

making member, insulating supporting means for said contact making members, the insulating support of said main contact making member being mounted for rotative movement, a collapsible link connection between said contact making members for transmitting motion from one of said contact making members to the other contact making member, and a sleet shield carried by said link connection and adapted to enclose said main contact making member when the switch is open.

5. A switch comprising a main contact member, an auxiliary contact member, an insulating support for said members, a main contact making member, a pivotally mounted auxiliary contact making member, a movable insulating support for said main contact making member, a stationary insulating support to which said auxiliary contact making member is pivoted, means for swinging the auxiliary contact making member upon movement of the movable insulator support, and a pin carried by said movable insulating support having a counter balancing weight attached thereto.

6. A switch comprising a base, an insulating support mounted upon each end of said base, a main contact member and an auxiliary contact member carried by one of said supports, an auxiliary contact making member pivoted upon the other support, a movable insulating support pivotally mounted on said base between said supports, a main contact making member mounted upon said movable insulating support, and a link connected between said main and auxiliary contact making members for swinging the auxiliary contact making member.

7. A switch comprising a base, an insulating support mounted upon each end of said base, a main contact member and an auxiliary contact member carried by one of said supports, an auxiliary contact making member at least partially carried by the other support, a movable insulating support pivotally mounted on said base between said other supports, a main contact making member mounted upon said movable insulating support, a collapsible link connection between said main and auxiliary contact making members for swinging the auxiliary contact making member, and means for operating said movable insulating support to bring said auxiliary contact members into engagement before said main contact members.

8. A switch comprising a base, an insulating support mounted upon each end of said base, a main contact member and an auxiliary contact member carried by one of said supports, an auxiliary contact making member supported by means including the other of said supports, a movable insulating support carried by said base and pivotally mounted thereon between said other insu-

lating supports, a main contact making member carried by said movable insulating support, a link connection including a pivoted joint between the contact making members, means for operating said movable support to bring the main contact members into engagement, means for operating said movable insulating support to open said main contact members while said auxiliary contact members are maintained in engagement, and for then opening said auxiliary contact members with a rapid snapping motion.

9. In an electric switch, a stationary contact, and a stationary arcing horn, a movable contact and a movable arcing horn, means for moving the last mentioned contact and horn into and out of engagement with the first mentioned contact and horn, respectively, said means including a lost motion connecting linkage between the movable contact and the movable horn for initially actuating the horn subsequent to the actuation of the contact, and a sleet hood swung by said linkage in to and out of a position enclosing the movable contact.

10. In an electric switch, a stationary insulator, a movable insulator, a pair of cooperating main contacts mounted on the respective insulators, a second stationary insulator, a pair of cooperating auxiliary contacts mounted on the respective stationary insulators, and a lost motion connection between the movable insulator and one of the auxiliary contacts for moving the auxiliary contacts into and out of engagement with one another.

11. A switch comprising a base, insulators mounted thereupon, a pair of stationary terminals supported on the insulators, a movable insulator between said terminals, a switch contact provided with arcing horns connected to one terminal, a movable arm comprising a second arcing horn connected to the other terminal and cooperable with the first arcing horn, a second switch contact carried by said movable insulator and electrically connected to said other terminal, and a lost motion coupling between the movable insulator and said arm for causing the arm to close the arcing horns before the switch contacts are closed and open them after the switch contacts have opened.

12. A switch comprising a base, insulators mounted thereupon, a pair of stationary terminals supported on the insulators, a movable insulator between said terminals, a switch contact provided with arcing horns connected to one terminal, a movable arm comprising a second arcing horn connected to the other terminal and cooperable with the first arcing horn, a second switch contact carried by said movable insulator and electrically connected to said other terminal, a lost motion coupling between the movable insulator and said arm for causing the arm to close

the arcing horns before the switch contacts are closed and open them after the switch contacts have opened, and a sleet hood operated by the coupling for covering and uncovering one of said switch contacts.

13. A disconnect switch including a main contact having an arcing contact associated therewith, a cooperating contact making member having an arcing member associated therewith, stationary and movable insulators supporting the two last mentioned members, means including the movable insulator for moving the main contact making member out of its circuit closing position, and a lost motion connection for thereafter initiating the movement of the associated arcing member, said lost motion connection comprising a pair of links pivotally connected together and having at one end a pivotal connection with the arcing member and at the other end a pivotal connection with the movable insulator.

14. A switch comprising a base, a four pivoted link mechanism mounted thereon about two stationary spaced pivots, one end link being mounted on one of the pivots and comprising a rocking insulator, the opposite end link being mounted on the other pivot and comprising an arcing contact, the two other links being connected together and connecting the two first mentioned links, and a stationary insulator supporting the last mentioned pivot.

15. A switch comprising a stationary insulator, a rocking insulator movable towards and away from the stationary insulator, a contact making member carried by the rocking insulator, an arcing contact pivotally mounted on the stationary insulator, and a pair of pivotally connected links having a pivotal connection at one end to the arcing contact and at the other end to the rocking insulator.

16. A switch comprising a stationary insulator, a rocking insulator movable towards and away from the stationary insulator, a contact making member carried by the rocking insulator, an arcing horn pivotally mounted on the stationary insulator, a pair of pivotally connected links having a pivotal connection at one end to the arcing horn and at the other end to the rocking insulator, and a sleet shield at one end of said links and movable thereby into and out of a position covering said main contact.

17. A switch comprising a stationary insulator, a rocking insulator movable towards and away from the stationary insulator, a link pivoted on the stationary insulator, a link pivoted on the rocking insulator, a third link pivoted to each of said links and maintaining a pivotal connection between them, and means independent of the two last mentioned links for maintaining the first mentioned link in its switch closed position.

18. A switch comprising a stationary insulator, a rocking insulator movable towards and away from the stationary insulator, a link pivoted on the stationary insulator, a link pivoted on the rocking insulator, a connection between the two pivoted links, and an arcing horn carried by said first mentioned link.

19. A switch comprising a stationary insulator, a rocking insulator movable towards and away from the stationary insulator, a link pivoted on the stationary insulator, a link pivoted on the rocking insulator and a lost motion connection between the two links.

In witness whereof I hereunto subscribe my name this eleventh day of August, 1927.

JOHN SCHNEIDER.
